FIG. 1

Figure 1 is a front perspective view of a combined medicinal vaporizer and holder therefor or the like showing my new design;

The dominant features of my new design reside in the full line portions of the drawing.

I claim:

The ornamental design for a combined medicinal vaporizer and holder therefor or the like, substantially as shown and described.
